INVENTOR:

Carmine M. Carmeroto,

BY

Ole M. Holmgren
HIS ATTORNEY.

UNITED STATES PATENT OFFICE.

CARMINE M. CARMEROTO, OF NEW YORK, N. Y.

FIRE-TOOL SUPPORT.

Application filed December 20, 1922. Serial No. 607,985.

To all whom it may concern:

Be it known that I, CARMINE M. CARMEROTO, a citizen of the United States, residing in the borough of Bronx, county of Bronx, city and State of New York, have invented certain new and useful Improvements in Fire-Tool Supports, of which the following is a specification.

This invention relates to supports, and particularly to a support for fire tools adapted to be rigidly secured to a pipe which may form part of a heating plant or apparatus, or to any other suitable holding device.

It is a well known fact that the fire tools used in connection with heating apparatus are usually given scant attention, being allowed to stand in corners of the cellars or other places where the heating plant may be located, or carelessly hung on nails or hooks loosely driven into the brick work of the chimney walls or foundation of the building. The inconvenient location of the fire tools often leads the operator to disregard them so that they are not used regularly, thus materially reducing the efficiency of the heating plant. The hanging of the tools on insecure supports also frequently constitutes a danger to any one accidentally running against or touching them. The above conditions dictate the necessity for a practical, conveniently located and securely held fire tool support which will prove an incentive to the regular use of the tools and the proper care of the boiler or furnace.

The primary object of my present invention is to enable the fire tools, such as the poker, brush, flue cleaner, and other devices used in conjunction with a steam or hot water boiler or furnace to be supported within convenient reach of the operator.

A further object is to construct the fire tool support in one piece, with suitable securing means, so that the support may be cheaply manufactured and quickly and easily secured to one or more of the pipes of the heating apparatus, or to any other convenient holding device.

With the above and other objects in view, which will later appear, I have devised the support for fire tools described in the following specification and illustrated in the accompanying drawing, forming a part hereof, in which—

Figure 1 is a front view of a heating

boiler showing my device in operative position, attached to a vertical section of the piping;

Figure 2 is a perspective view of the support;

Figure 3 is a view of the securing end of the support; and

Figure 4 is a perspective view showing a modification of the fire tool support which is adapted to be secured between two parallel horizontal pipes.

Referring further to the drawings, the support is shown in its preferred form in Figures 1, 2 and 3, and consists of a longitudinally extending bar or bracket member A of substantially uniform thickness throughout, having a plurality of depending portions B, the width of the depending portions B gradually decreasing toward the ends C. These ends C are turned upwardly toward the bracket A so that they are substantially parallel with the sides of the bracket, thus forming a series of hooked portions D. These hooks D may be of any desired number and are so spaced from each other as to provide relative large open spaces between the hooked portions.

The outer end of the bar A curves downwardly gradually, as shown at E, and forms the last hook F of the series. The opposite end of the bar is formed into two arcuately diverging arms G, the lower portions H and sides J of which merge and gradually decrease in area and thickness, forming a bottom brace K. The arms G and brace K together present a curved surface L which is adapted to partly embrace a cylindrical pipe or other suitable support, such as a riser O extending vertically upward from the boiler P.

The arms G are provided with lugs R which extend outwardly substantially at right angles to the arms G. The bar A, hooks D and F, arms G and brace K are all formed in one piece. The device is adapted to be secured to the pipe O or other support by a substantially semi-circular U-bolt or other clamping device S, which is adapted to embrace the opposite side of the pipe O. The ends of the clamp S are adapted to pass through holes T in the lugs R and are secured by nuts U threaded on the ends V of the clamp. If desired, a bolt head may be formed on one end V of the clamp so that it will only be necessary to provide the nut U at one end of the clamp.

When the nuts U are screwed up the fire tool support will be securely held on the pipe O or other support, against vertical or oscillatory movement. The location of the 5 clamping means at a point substantially in the plane of the top of the bar A causes the weight of the fire tools, here illustrated as a poker W, flue cleaner X and brush Y, to be borne by the brace K which rests flush 10 against the face of the pipe O and is of such length as to adequately brace the entire structure. The brace K tapers gradually so that the lower end Z is quite thin and meets the face of the pipe O, thus presenting a 15 neat appearance when in use.

In the modification of the invention illustrated in Figure 4 the device is shown in a form adapted for attachment to pipes which usually run close to the ceiling, or other 20 supports which may be located in a non- vertical position. In this form the bracket or bar —a— and hooks —b— are constructed in the same manner as described in connection with the preferred form. Both ends 25 —c— of the bar —a— curve gradually downward to form the end hooks —d—, and each of the ends —c— is formed with diverging arms —e— which are adapted to present a curved surface —f— to embrace 30 one of the pipes —g—. The arms —e— are clamped about the pipes —g— by U- bolts or other clamping devices —h— in the same manner as in the preferred modification already described, and are adapted to 35 brace the support against any swinging movement.

It is to be understood that while the present showing and description discloses certain specific embodiments of the present invention, other forms and modifications are included within the spirit and scope thereof, as expressed in the appended claims.

I claim:

1. A support for fire tools, comprising a 45 longitudinal bar having a plurality of uniform depending portions, the ends of said depending portions being upturned to form a series of hooks, said hooks being separated

from each other to provide relatively large open spaces between the hooks, the outer end 50 of said bar being contoured to form the last hook of the series and the opposite end of the bar being formed into two arcuately diverging arms, the lower portions and sides 55 of said arms merging and gradually decreasing in area and thickness to form a bottom brace, said arms and brace together presenting a curved surface adapted to partly embrace a cylindrical support, and lugs extending substantially at right angles from the 60 ends of said arms, all being formed in one piece, and a substantially semi-circular clamp adapted to embrace the opposite side 65 of said cylindrical support, the ends of said clamp passing through said lugs, and nuts for rigidly securing said clamp and arms about the support.

2. A support for fire tools, comprising a longitudinal bar having three substantially uniform depending portions, the ends of 70 said depending portions being upturned to form a series of hooks and extending upwardly to a point substantially in a plane with the body of the bar, said hooks being separated from each other to provide relatively large open spaces between the hooks, the outer end of said bar being contoured to form the last hook of the series and the opposite end of the bar being formed into two arcuately diverging arms, the lower portions 75 and sides of said arms merging and gradually decreasing in area and thickness to form a bottom brace, said arms and brace together presenting a curved surface adapted to partly embrace a cylindrical support, 80 and lugs extending substantially at right angles from the ends of said arms, all being formed in one piece, and a substantially semi-circular clamp adapted to embrace the opposite side of said cylindrical support, 85 the ends of said clamp passing through said lugs, and nuts for rigidly securing said clamp and arms about the support.

In testimony whereof, I have affixed my signature to this specification.

CARMINE M. CARMEROTO.
